DISPLAY RACK

Ted Hill, Chicago, Ill.

Application February 9, 1935, Serial No. 5,706

3 Claims. (Cl. 211—85)

This invention relates to display racks and particularly to such devices designed for displaying cans of oil and other packaged products.

The main objects of this invention are to provide an improved display rack construction in which rows of cans and the like are securely supported without the use of the usual shelving; to provide an improved display rack of sturdy simplified structure and low cost of manufacture; to provide such a device that is foldable into a compact form for shipping purposes; and to provide such a device that is of light-weight, self-supporting and particularly capable of standing upright against a wall like shelving but readily foldable without increasing its projected base area.

A specific embodiment of this invention is shown in the accompanying drawing, in which:

Fig. 1 is a perspective view showing the improved rack in set-up position.

Fig. 2 is a sectional side view of the same showing the manner of folding.

Fig. 3 is a fragmentary enlarged sectional view of the top portion of the same, and

Fig. 4 is an enlarged fragmentary detail showing the joint between the folding portions of the rack.

As shown in the drawing my improved and simplified display rack comprises spaced vertical end members between which two vertical rows of horizontal cross bars are arranged, the cross bars joining the end members and the rows being disposed along or adjacent opposite edges of the end members with the cross bars of the rear row staggered upwardly relative to those of the front row. Feet are provided so that the rack is self-supporting and capable of standing against a wall without being fastened thereto. The device is made in upper and lower sections hinged together at the front so that the upper section may be folded downwardly against the lower section to form a compact package for shipping and storage.

The rack is preferably a welded sheet metal construction and the cross bars are so formed and arranged that a can or package resting upon a bar of the front row and against a higher bar of the rear row will be supported firmly in a backwardly inclined position, but with its center of gravity near the front of the rack, the spacing of the front and rear bars relative to each other being such that the can or package can not be pushed or jarred so as to fall between the bars.

In the form shown in the drawing the vertical side members 1 of the improved rack are formed of sheet metal bent into the shape of channels of predetermined width and are positioned in parallel relation and facing bosom to bosom with the flanges 2 extending toward each other. The side members are spaced apart and are connected to

gether by the cross bars which support the cans or packages to be displayed.

The horizontal cross bars 3 which comprise the front vertical row are, in the form shown, made from sheet metal bent to form an angle-bar and are secured to the side members by welding, or otherwise fastening, one leg to the forward flange of the side members, the other leg extending rearwardly. As shown the included angle between the legs of the bars 3 is such that the rearwardly extending leg is inclined downwardly.

This leg is preferably substantially flat and is inclined an amount sufficient to lie flatly against the bottom of a can or package 4 resting thereupon at the desired degree of inclination as shown in Fig. 3.

The inner margin 5 of the rearwardly extending leg is preferably turned downwardly to provide rigidity to the inner supporting edge; and the margin 6 of the other leg is turned outwardly and back upon itself to provide a pocket for a price card or the like, 1. The outwardly turned margin 6 of the cross bar 3 extends slightly beyond the front flanges 2 of the side members 1 and, while the construction is not shown in detail, it will be understood that the ends of the margin 6 are cut away to accommodate the flanges 2 upon the inner side of which the cross bar 3 is secured.

The cross bars 8 which comprise the rear row are V-shaped members, the margins of which are turned outwardly at right angles to the center line of the angle between the sides of the V and these turned out margins are welded or otherwise secured against the inner side of the rear flanges of the side members.

As shown the front and rear cross bars 3 and 8 respectively are arranged in pairs, a cross bar 8 for each cross bar 3.

Thus a can or package resting upon a cross bar 3 rests against a cross bar 8, the vertical spacing between respective pairs of cross bars 8 and 3 being such that the cross bar 8 will engage the can or package at a point near its upper end.

The vertical spacing of the front cross bars 3 is predetermined to accommodate certain sizes of packages and the spacing between the front and rear rows of cross bars, as determined by the depth of the display rack, is such that the package will be held securely in an upwardly and backwardly inclined position and so that there will be no likelihood of the can or package being inadvertently pushed or jarred so as to fall between its supporting cross bars.

As shown in Figs. 1 and 2 the display rack is provided with outwardly projecting vertically triangular feet 9 which are formed from sheet metal and secured by any suitable means against the outer face of each of the vertical side members 1, the feet 9 projecting forwardly from the front edge of the side members 1 and the upper

margin of the feet being inclined outwardly and downwardly.

As shown in Figs. 1 and 2 a cross bar 31 is secured to the forwardly projecting portions of the feet 9 and provides a support for a can or package of larger size than would be accommodated by the remaining cross bars of the display rack.

As shown in Figures 1, 2 and 4, the display rack is formed in two sections, an upper section 10 and a lower section which are hinged together on the front side of the rack. This is accomplished by making each of the side members 1 in two parts and hinging these parts together by any suitable hinge arrangement such as that indicated at 10 on the forward edge of the side members. In order to lock the upper and lower sections of the rack together in a set-up position, and to hold the two sections in proper alignment, an angle piece 11 is fastened between the web 20 and the rear flange of each lower portion of the side members, so as to overlap the joint between the upper and lower portions, and alined holes 12 are provided in each angle 11 and upper side member section to accommodate a bolt 13 25 which effectively locks the upper and lower sections of the rack together.

As shown, the upper end of the display rack is mitered as at 14, so that when the upper section is folded forwardly against the lower section 30 as shown in Fig. 2, the free end of the upper section will fit the vertically triangular feet 9. Thus when the rack is folded its vertical height will be substantially half of that in its set-up position, the projected floor area of the rack 35 will not be increased and the entire device will form a compact and solid package for shipping purposes.

As shown in the drawing means for holding a display card are provided at the upper end of each side member and on the outer side of the rear flange thereof. Such means comprise sheet metal pockets 15 which are formed so as to be open at the tops and along the inner or mutually facing ends and are welded or otherwise secured on the rear flanges 2. The pockets 15 are preferably made to be substantially as long laterally as the width of the flange 2 and deep enough to furnish ample support for the display card 16 shown in dotted outline in Fig. 1. 40 Thus a display card made of substantially rigid or stiff material, or having a reinforced lower edge may be positioned with its lower corners inserted in the pockets 15 and suitably supported at the same time being readily removable for change.

The thickness of the pockets 15 is preferably just sufficient to receive the card 16 and the projection beyond the back of the display rack will therefore not interfere with setting the rack 45 tightly against a wall, particularly since in indoor use the rack must usually be placed against a base board which extends outwardly from the wall surface and thus leaves ample room for the projecting pockets 15.

65 The main advantages of my improved display rack are in its simple and light weight construction, which employs a minimum amount of material and which can be readily manufactured of sheet metal stampings which can be economically assembled by welding. The arrangement of cross bars obviates the necessity of providing the

usual shelves which would extend for substantially the entire depth of the rack and yet the cans or packages that are displayed in the device are securely held in such a position that they may be most readily examined by a purchaser. Also because of their sturdy construction and low cost of manufacture, my improved display racks are particularly suitable for outdoor use, such as in gasoline stations and the like. 5

10 Although but one specific embodiment of this invention is herein shown and described, it will be understood that details of the construction shown may be altered or omitted without departing from the spirit of this invention as defined by the following claims.

I claim:

1. A display rack comprising spaced vertical side members, a plurality of horizontal vertically spaced cross bars secured to and extending between said side members, other vertically spaced horizontal cross members secured to and extending between said side members and disposed a predetermined distance behind the first named bars, said other cross bars being one for each 25 of the first named bars and arranged in upwardly staggered relation thereto, and said side members each comprising upper and lower sections hinged together on one edge whereby the upper portion of said rack is foldable downwardly 30 against the lower portion thereof.

2. A display rack comprising spaced vertical side members, a plurality of horizontal vertically spaced cross bars secured to and extending between said side members, other vertically spaced 35 horizontal cross members secured to and extending between said side members and disposed a predetermined distance behind the first named bars, said other cross bars being one for each of the first named bars and arranged in upwardly staggered relation thereto, and vertically triangular feet projecting from the edge of said side members at the bottom of one side of said rack, said side members each comprising upper and lower sections hinged together on the edge 40 from which said feet project whereby the upper portion of said rack is foldable downwardly against the lower portion thereof, and said side members having their upper ends mitered to substantially fit the upper edge of said triangular feet when said rack is folded. 45

3. A display rack comprising a pair of spaced vertical sheet metal channels arranged with their flanges projecting toward each other, a plurality of horizontally disposed vertically spaced angle 55 bars connecting said channels and secured to the flanges thereof on the front side of said rack, said angle bars each having one leg secured to said flanges and extending downwardly and the other leg extending rearwardly and inclined 60 downwardly, and a plurality of other vertically spaced horizontal angle bars extending between and secured to the rear flanges of said channels, said other bars being one for each of the first named bars and staggered upwardly a predetermined 65 distance relative thereto, whereby a package resting upon the inclined leg of one of the front bars will rest against a respective one of the rear bars in a rearwardly inclined position.
